WELL CASING FOR LATERAL BORES

John A. Zublin, Los Angeles, Calif.

Application May 10, 1944, Serial No. 534,930

6 Claims. (Cl. 166—4)

This invention relates to an improvement in well casings, more particularly as applied to the casing of lateral bores. In its specific aspects, the invention contemplates the provision of means for closing the opening in a vertical well casing around a lateral casing and to more or less interlock the vertical and lateral casings.

In my earlier Patents No. 2,336,334 and No. 2,336,338, I have disclosed means and methods for producing deviating bores that extend laterally from an existing vertical well bore. To permit the drilling and subsequent casing of these deviating bores, it is usual to cut elongated windows or openings in the wall of the casing of the existing vertical well, the lateral drilling operation and subsequent casing of the lateral bore being effected through such window or opening. A suitable casing for use in casing a lateral bore deviating from a vertical bore has been disclosed and constitutes the subject matter of my copending application Serial No. 517,559, filed January 8, 1944.

The present invention has for its purpose the provision of means for closing the window or opening in the wall of the vertical casing around the casing that projects into the lateral bore, so as to avoid any deleterious effects of material that may cave in from the upper wall of the deviating bore, and to provide an effective interlock at the point of juncture of the vertical and lateral casings while, at the same time, leaving the vertical casing open both above and below the lateral bore to permit of continued production therefrom and, if need be, the operation of pumping equipment or the like in that portion of the vertical casing below the lateral bore.

More detailed and specific objects of the invention will become apparent as the description of the invention proceeds, which will be given with reference to the accompanying drawings, wherein:

Figure 1 is a side elevational view, partly in section, showing a preferred embodiment of the invention in process of being introduced into the well;

Fig. 2 is a detailed view showing the embodiment of Fig. 1 after the lateral casing and window closing means have been fully installed;

Fig. 3 is an enlarged detailed sectional view of the embodiment of Fig. 1, showing the position of parts as the casing and closing means are being introduced into the well;

Fig. 4 is a further enlarged sectional view showing the position of parts after the lateral casing

enclosing means have been brought to final position;

Fig. 5 is a cross-sectional view on the line 5—5 of Fig. 3;

Fig. 6 is a cross-sectional view on line 6—6 of Fig. 4;

Fig. 7 is a side elevational view with parts in section showing a second modification of the invention in process of being introduced into a well;

Fig. 8 is an enlarged sectional view of the shield closing means of Fig. 7;

Fig. 9 is an elevational view of the window closing shield of Fig. 7;

Fig. 10 is an enlarged sectional view showing the closing shield of Fig. 7 in its final installed position in the well;

Fig. 11 is a cross-sectional view on line 11—11 of Fig. 10;

Fig. 12 is a cross-sectional view on line 12—12 of Fig. 10;

Fig. 13 is a cross-sectional view on line 13—13 of Fig. 10;

Fig. 14 is a view of still another modification of the invention showing the closing means in its final installed position in the well;

Fig. 15 is a sectional view showing the embodiment of Fig. 14 in process of being introduced into the well;

Fig. 16 is an elevational view of the embodiment of Fig. 14 removed from the well casing;

Fig. 17 is a cross-sectional view on the line 17—17 of Fig. 14; and

Fig. 18 is a cross-sectional view on line 18—18 of Fig. 15.

Referring to Fig. 1, the existing vertical well 1 from which the lateral bore 2 has been drilled, is provided with the usual vertical well casing 3 through the wall of which the window 4 is cut to permit of drilling of the lateral bore, such as 2, in accordance with the teachings of my prior patents hereinbefore referred to. After the lateral bore 2 has been completed, it becomes necessary to insert a suitable well casing into the lateral bore to preclude premature shutting off of the lateral bore through cave-ins and the like.

To this end, I have heretofore provided and adapted a flexible casing such as indicated at 5 for insertion into the lateral bore. The forward or free end of the flexible casing 5 is conveniently provided with a tapered nose 6 which is desirably apertured as at 7 for a purpose to be presently described.

The rear or trailing end of the flexible casing 5 is adapted to be threadedly received as shown at

8 (Fig. 4) in a shield or closure member indicated generally at 9 for effectively closing the window 4 of the casing 3 when in finally installed position, as more fully shown in Fig. 2.

By reference to Fig. 5, it will be noted that the shield 9 is concentric with the casing 3 and adapted, when in finally installed position as shown in cross-section in Fig. 6, to extend something over one-quarter of the distance around the inner surface of the casing 3. The arcuate shield 9 is provided with the projection 10 into which the casing 6 is threadedly received as shown at 8. The projection 10 lies substantially outside the inner circumference of the casing 3 and is provided with a second set of threads, in this instance left-handed threads, 11 for receiving the lower end 12 of a flexible tube 13 which, in accordance with this embodiment of the invention, extends to the surface of the well and can be used for lowering the flexible casing 5, shield 9, and its attendant parts to be presently described, into the well.

A hose 14 is adapted to extend from the surface of the well through the tube 13 and into the flexible casing 5. Fluid can be introduced through the hose 14 and forced out through the opening 1 in the nose 6 to flush the lateral bore 2 in advance of the casing 5 as the latter is inserted into the lateral bore.

The shield 9 is adapted, during the process of being lowered into the well, to be interlocked through the medium of the collar 15 and shear pins 16 with the tube 17. The upper end of the tube 17 is completely cylindrical, thus lining the casing 3. The tube 17 is, however, progressively cut away first along the inclined face 18 and vertical line 19, and then along the inclined face 20 and vertical line 21 (Fig. 2). The upper end of the shield 9 is cut along inclined face 22 at the same inclination as the faces 18 and 20. When the shield 9 and the tube 17 are interlocked to be lowered into the well as shown in Fig. 1, the inclined upper end 22 of the shield 9 abuts the inclined face 20 at the lower cut away portion of the tube 17, and the collar 15, with its shear pins 16, holds the shield 9 and tube 17 in this position.

When the guide fin 23 on the shield 9 reaches the window 4 in the casing 3, there is a tendency for the shield 9 and the lower end of the tube 17 to be canted toward the window 4. This canting movement is resisted to some extent by the cylindrical portion at the upper end of the tube 17. At this point, the flexible tube 13 may have its lower end 12 unscrewed from the threads 11 in the shield 9, permitting the elevation at the surface of the well of the tube 13 and the concurrent withdrawal of the hose 14 from the lateral flexible casing 5.

When the hose 14 has been withdrawn from the flexible casing 5, the tube 13 is again lowered, but at this time the hose 14 and the tube 13 merely project down into the vertical casing 3 below the lateral bore 2 as indicated in Fig. 4, it being understood that the tube 13 passes freely through the interior of the shear pin carrying collar 15. There is affixed to the tube 13 at an appropriate position thereon, a collar 24 which is adapted, when the tube 13 is lowered in the manner indicated in Fig. 4, to strike the upper face 25 of the tube 17 and to impose sufficient weight on the face 25 of the tube 17 to shear the shear pins 16 and drive the tube 17 downwardly, forcing the shield 9 downwardly and outwardly until it occupies the position shown in Fig. 2, at which time the inclined upper end 22

of the shield 9 abuts the inclined face 18 of the tube 17 and the complete assembly comes to rest with the shield 9 acting effectively close the window 4 in the casing 3 and interlock the flexible lateral casing 5 with the vertical casing 3. It will be appreciated that the shield 9 and the tube 17 may be cut from an elongated tube of slightly less diameter than the casing 3. It is likewise apparent that when the shield 9 and tube 17

5 are moved to the finally installed position shown in Fig. 2, the vertical casing 3 is open, being only reduced in diameter at the point of installation by the thickness of the wall of the tube 17. In this way, the vertical well is in no way impaired by virtue of the drilling and casing of the deviating bore 2.

Referring next to the modification of Figs. 7 to 13, it will be observed that a highly simplified form of shield for closing the window 4 in the 20 casing 3 has been provided. In this modification, the flexible lateral casing 5 has its terminal end threadedly received in the shield 9a as indicated at 8a. The shield 9a has a short tubular portion 9b at its upper end and a terminal locking lip 9c 25 at its lower end.

Fig. 7 illustrates the position occupied by the shield 9a and the flexible casing 5 during the lowering of the same into the well. In Fig. 10, the shield 9a is shown in the position that it occurs when fully installed in the well, in which position the lip 9c interlocks with the casing 3 below the flexible casing 5. In this modification, the flexible casing 5 and the shield 9a are adapted to be lowered into the well through the medium 35 of a fishing tool designed for and capable of gripping the upper tubular end 9b of the shield 9a, and to permit of the application of sufficient force thereto to drive the shield 9a into fully installed position.

40 By reference to the sectional views of Figs. 11, 12 and 13, it will be observed that the shield 9a effectively closes the window 4 of the casing 3, and also interlocks the flexible casing 5 with the vertical casing 3. In this modification, as in the 45 modification of Figs. 1 to 6, the vertical casing 3 is left open for continued production from the vertical well as it existed prior to the drilling and casing of the deviating bore. It will therefore be appreciated that any conventional 50 pumping equipment such as indicated generally at X in Fig. 10, may be installed and operated within the vertical casing 3 below the lateral bore 2 after the installation of the flexible casing 5 and shield 9a.

55 Coming next to the modification of the invention shown in Figs. 14 to 18, it will be observed that in this modification the window closing and casing interlocking device takes the form of a tubular section 26 having a pivoted specially constructed section 27. The section 27 is formed 60 at its upper end with an arcuate hinge section 28 adapted to be seated in a complementary hinge recess 29 in the tubular member 26. The section 27 is adapted to project through the window 4 in the casing 3 as indicated at 30 and to receive the threaded end 31 of the flexible casing 35. The shield section 27 also carries the downwardly projecting lip 32 which is adapted to interlock with the casing 3 at the bottom of window 4 as shown at 33 (Fig. 14).

65 In this modification, as in the modification of Figs. 7 to 13, the entire device including the flexible casing 5 is adapted to be lowered into the vertical well casing 3 through the medium of 70 an appropriate fishing tool adapted to be received

within and to clamp the upper end of the tubular section 26. In both the modifications of Figs. 7 to 13 and Figs. 14 to 18, the flexible casing 5 may be flexed before introduction into the well in such manner as to ensure its continuing tendency to take the curvature of the deviating bore as the same is inserted thereinto with the result that when the flexible casing 5 is fully inserted and the shield 9a or tubular member 26 reaches its final position of adjustment, the shield section will extend outwardly of the window 4 into the deviating bore and effectively close the window around the casing 5 without blocking the vertical casing 3.

It will be observed that in the final position of adjustment of the window closing shield, the vertical casing 3 is open, being reduced in diameter at the point of installation of the window shield closing device only by the thickness of the wall of the shield 9a or the tubular section 26.

From the foregoing specification and the accompanying drawings it will be apparent that I have provided a novel and effective means for closing a window or opening in a vertical well casing upon completion of the drilling and casing of a lateral bore deviating from a vertical well in which such vertical casing is disposed. It is to be understood that the foregoing description is given by way of illustration and exemplification of the invention, and not in limitation thereof; the scope of the invention being that comprehended by the subjoined claims.

I claim:

1. A shield for effectively closing an opening in the wall of a vertical well casing surrounding a laterally extending casing projecting from the vertical casing, said shield comprising a vertically elongated arcuate member, an offset portion carried by said shield, a threaded opening in said offset portion for threadedly receiving the trailing end of a lateral casing, said offset portion being so related to the vertically elongated arcuate portion of the shield that it lies substantially outside the inner circumference of a vertical well casing when said shield and laterally extending casing have been installed and limits the downward movement of said shield.

2. In combination, a flexible oil well casing capable of insertion in a lateral bore, deviating from a vertical bore, through a window in a vertical well casing in said vertical bore, closing means interconnectable with said flexible casing

for closing the window about said flexible casing adapted to be brought into closing relation with the window and to extend above and below the same within the vertical casing when said flexible casing is fully inserted in the lateral bore.

3. In combination, a flexible oil well casing adapted to be inserted into a lateral bore deviating from a vertical bore through an opening in a vertical casing disposed in said vertical bore, a shield carried by the trailing end of said flexible casing, said shield being curved to substantially conform to the wall of a vertical well casing, and adapted when installed to extend within the vertical casing above and below the point of juncture between the flexible casing and a vertical casing in the vertical bore.

4. In combination, a flexible oil well casing capable of insertion in a lateral bore, deviating from a vertical bore, through a window in a vertical well casing in said vertical bore, closing means for closing the window about said flexible casing and adapted to be brought into closing relation with the window when said flexible casing is fully inserted in the lateral bore, said closing means including means cooperating with the window wall for holding said closing means against displacement after the same is brought into closing relation with said window.

5. In combination, a vertical well casing, a window in said casing, a second casing adapted to be projected through said window and inserted in a lateral well bore, means insertable through said vertical casing and so associated with said second casing as to close said window around said second casing when said second casing is fully projected through said window, said closing means including means cooperating with the window wall for holding said closing means against displacement after the same is brought into closing relation with said window.

6. In combination, a flexible oil well casing adapted to be inserted into a lateral bore deviating from a vertical bore through an opening in a vertical casing disposed in said vertical bore, a shield carried by the trailing end of said flexible casing, said shield being curved to substantially conform to the wall of a vertical well casing and adapted when installed to extend within the vertical casing above and below the point of juncture of the flexible casing and a vertical casing, and means for holding said shield against displacement when installed.

JOHN A. ZUBLIN.
